UNITED STATES PATENT OFFICE.

ROBERTO KURTZ, OF BUENOS AIRES, ARGENTINA.

ROAD SCRAPER.

Application filed September 2, 1921. Serial No. 497,884.

To all whom it may concern:

Be it known that I, ROBERTO KURTZ, a citizen of the Argentine Republic, and resident of Buenos Aires, Argentine Republic, have **5** invented certain new and useful Improvements in Road Scrapers, of which the following is a specification.

This invention refers to a simple and elemental apparatus commonly known as a **10** "road scraper", usually drawn by horses or oxen, guided by a workman and used for excavating and transporting soil.

The invention has for its object certain **15** improvements introduced in the construction of such apparatus, whereby it is possible to obtain the automatic loading and discharging of same, and at the same time the scraper is caused to make automatically a cut of uniform depth, thus effecting an **20** important economy of labor, and at the same time diminishing and making more uniform the force exerted by the draft animals.

A preferred form of the invention is **25** illustrated in the accompanying drawings, in which Fig. 1 is a perspective view of the scraper; Figs. 2, 3, 4, 5 and 6 are side elevations in different operative positions, of the same, and Figs. 7 and 8 are details of **30** the hook and latch system.

Construction.

The automatic scraper is composed of **35** two parts: (1) the scraper body and (2) the frame.

The scraper body is a box made of iron plates, open at the top and front. To the front part of the bottom plate is fixed a pointed blade J, Fig. 1. At the top of both **40** sides, and ahead of the vertical plane which contains the centre of gravity of the empty scraper, are riveted the standards s, s' for the bolts I I' which connect the body of the scraper to the frame.

The entire body is constructed in such a **45** way that the centres of gravity of the scraper when empty or full will be situated with relation to the edges of the bottom in the required conditions of operation **50** which will be hereinafter explained.

The frame is composed of a structure H consisting of an iron tube conveniently curved. This structure is closed at the rear by a cast iron piece D which supports

by means of the small frame A the hook P. **55** The bolt E traversing two small brackets of the cast iron piece D, serves as an axis for the movement of the latch K.

At the sides of the structure H by means of the brackets d d' are fastened the chains **60** a a' for traction purposes.

Within the frame the scraper body can describe a complete circular rotation and in a certain relative angular position it remains fixed by the hook L engaging the **65** latch K.

The rope S when embracing the hook P exerts a pull on the whole frame as shown in Fig. 2 and when it does not embrace the hook P it exerts a pull on the latch K only, **70** and disengages the hook L as shown in Fig. 4.

Operation.

1. *The transportation of the empty or loaded scraper.*—The rope S being slack, traction is exerted directly on the brackets d d' and since the vertical of the centre of gravity passes behind the edge n of the bottom plate, the scraper is maintained in its **75** normal position, which is shown in Fig. 1; the scraper slides by friction of the part m, n of its bottom and may ascend or descend any incline.

2. *Loading.*—Pulling the rope S moderately, causes the whole system to slide by friction of the point of the blade on the soil. Thus what occurs is similar to what would occur with a plow. Point J penetrates in the ground, as shown in Figure 2, **80** until the front part of the structure H, which serves as a stop, touches the ground. The front part of the scraper bottom is caused to assume the horizontal position **85** and will have no more tendency to continue penetrating the soil. Thus the maximum predetermined depth will have been reached, as shown in Fig. 3.

It may be noted that this maximum depth depends on the position of part H of the frame, relatively to the scraper body, and this position, in turn, depends on that occupied by the hook L. The hook L may be placed higher or lower, by means of fastening bolts therein engaging the holes Z and **100** Z' so that the depth of the cut is decreased or increased, respectively, at will.

When the scraper is full, rope S is

loosened, and the scraper assumes the normal position, that is, the position shown in Fig. 1. The blade will then cut on an ascending incline and the scraper comes out 5 to the surface.

Discharging.—The driver by means of a "lasso stroke" prevents rope S from embracing the hook P and exerts a direct pull on latch K disengaging hook L as shown 10 in Fig. 4. The scraper body is now free to revolve inside the frame and the driver loosens again the rope S.

Traction will now be exerted on the bolts I. Assuming W to be the weight of the 15 loaded scraper and C the factor of friction, the minimum value of tension applied on I, will be W. C. and the static moment of this force in relation to the edge n, will be PC×In. If g is the intersection of the 20 bottom line with the vertical line drawn through the centre of gravity, the static moment of gravity with relation to the same edge will be P×gn. The scraper is constructed so that

$$25 \quad PC \times In > P \times gn.$$

Therefore, the scraper turns around the edge n until the blade J penetrates the soil, and the whole scraper body is then raised, 30 as shown in dotted lines in Figure 4, and tilted as shown by full lines in Figure 5. At this moment the vertical of the centre 35 of gravity of the empty scraper will pass in front of the bolts I I', and the body continues to turn by the action of its own weight until the edge o touches the ground.

It will be noted that latch K is maintained open, since it is constructed in such 40 a way that the under part drags on the ground at this moment. The open latch K thus leaves free pass for the blade J. When the points u u' touch the ground, the scraper body continues to rotate until it assumes the position shown in Figure 6. The frame 45 will have been raised, and latch K left to its own weight will have closed. When hook L touches the lower portion of the latch, it will cause it to assume the position of Figure 7, and when it strikes the surface 50 h causes it to close suddenly. This movement of the latch will depend in speed on the speed of that of hook L, and the closing operation will be automatic whatever 55 may be the speed of rotation of the scraper body.

This system is also applicable to cases 60 where there is no rider and the workman who manages the scraper holds the reins. Rope S is suppressed. The workman holding the reins walks behind the scraper and

operates directly by hand the frame A and latch K.

Having thus described and ascertained the nature of my said invention and the manner in which the same is to be performed, I declare that what I claim is:

1. An automatic road scraper of the character described including a substantially rectangular frame, a draft device connected with the forward portion of the frame, a single cavity scraper body rotatably suspended from the frame and automatically rotatable under the combined action of gravity and the draft exerted on the frame, a cooperating latching and locking device 70 mounted in the rear of the frame and on the rear of the scraper body and normally holding the scraper in operative position, and a flexible element permanently connected with the locking and latching element on the frame and temporarily engaged at times with the frame so as to maintain the latching and locking device in engaged position and facilitate the lifting of the frame to cause the scraper body to excavate, the flexible element being disengagable from the frame to release the scraper body so as to permit a complete rotation of the scraper body in the frame and insure an automatic 75 dumping and subsequent latching of the scraper body in an operative position in the frame.

2. An automatic road scraper as claimed in claim 1, in which the front portion of the frame constitutes a stop part for engaging the ground when the blade has penetrated the soil to a predetermined maximum depth.

3. An automatic road scraper as claimed in claim 1, wherein the front portion of the frame constitutes a stop part which engages the ground when the blade has penetrated the soil to a predetermined maximum depth and upon touching the ground causes the scraper blade to assume a horizontal position thus establishing a uniform depth of cut.

4. An automatic road scraper as claimed in claim 1, wherein the front portion of the frame constitutes a stop part for engaging the ground when the blade has penetrated the soil to a predetermined maximum depth, and the latching and locking element on the frame being vertically adjustable thereon to determine the depth of penetration of the 105 scraper blade with the ground.

Signed at Buenos Aires, Argentine Republic, this twenty-fifth day of July A. D. 1921.

ROBERTO KURTZ.
